LINE CASTING MACHINE

Samuel E. Sperry, Hollis, N. Y., assignor to Inter-type Corporation, Brooklyn, N. Y., a corporation of New York

Application November 14, 1933, Serial No. 697,979

9 Claims. (Cl. 199—50)

The present invention relates to improvements in line casting machines and more particularly to those of the class disclosed generally in U. S. Patent No. 436,532 granted September 16, 1890, wherein matrices bearing type forming characters are assembled in lines and the lines lowered by a transporter to a position in front of a mold in which type bars or slugs are cast against the matrix lines, the matrix lines being held in casting position in front of the mold by a vise, the jaws of which clamp the lines endwise.

Machines of this class are now provided with a movable vise jaw for quadding out short matrix lines or lines composed to less than full length for which the machine is set, the movable jaw being retained in normal or open position to receive the composed line by a suitable retaining latch, it being intended that the latch be released after the matrix line has been lowered substantially fully between the vise jaws, whereupon a closing device moves the jaw inwardly against the line to hold it for casting.

However, the line transporter or so-called first elevator which is ordinarily employed in machines of this class for lowering composed matrix lines between the vise jaws, must descend to varying extents in order to align matrices having type forming characters at different heights or levels thereon, properly in front of the slug casting mold, the machines being provided for this purpose with an alining bar which carries suitable positioning pieces for stopping the first elevator at the different required heights.

The primary object of the present invention is to provide means for releasing the movable vise jaw retaining latch at the proper time corresponding to the particular level to which the first elevator must descend. Heretofore it has been necessary to set the jaw retaining latch so that it was released when the first elevator came to rest at its high alinement position, so that if the elevator was set to stop at the normal or a lower alinement level, the jaw would be released while the elevator was travelling a considerable distance downwardly before coming to rest, and such excessive downward movement of the elevator while the jaw was closing against the line caused rubbing of the matrices at the ends of the line against the jaws, resulting in tilting the lower portion of the matrix line upwardly and toward the mold so that when the mold advanced to lock up against the matrix line with the lower lugs of the matrices out of alinement, the matrices were damaged. The present invention overcomes this difficulty by properly coordinating the oper-

ating relationship between the line transporter and the jaw retaining latch whereby release of the movable vise jaw is not effected until after the matrix line has been lowered by the elevator sufficiently far to insure proper alinement of the matrix line with the mold, irrespective of the alinement level at which the elevator comes to rest.

To these and other ends the invention consists in certain improvements and combinations and arrangements of parts all as will be hereinafter described, the features of novelty being pointed out more particularly in the claims at the end of this specification.

In the accompanying drawing:

Figure 1 is a front elevation, partly in section, of a portion of a line casting machine showing the preferred embodiment of the invention applied thereto;

Figure 2 is a top plan of a portion of the structure shown in Figure 1;

Figures 3 and 4 are transverse vertical sections on an enlarged scale through the mold and portions of the first elevator and adjacent parts, showing the first elevator respectively in positions to align matrix lines at different levels in relation to the mold;

Figure 5 is a side elevation of the structure shown in Figure 1, on a reduced scale, and showing the vise jaw closing means; and

Figures 6 and 7 are detail views, on an enlarged scale, showing the jaw retaining latch set for release by the first elevator while lowering matrix lines to different levels between the vise jaws.

Similar parts are designated by the same reference characters in the several figures.

In the embodiment of the invention shown in the accompanying drawing, 1 and 2 represent the usual right-hand and left-hand vise jaws as commonly used in machines of this class, these jaws being slideable in suitable guides in the cap 3 of the usual vise frame, so that they may move toward and from one another. The left-hand jaw 2 may be provided with the usual or any suitable setting and clamping means, such for example, as that disclosed in U. S. Patent No. 1,108,758 granted August 25, 1914, the adjusting knob 2a and adjusting rod 2b of which are shown, and the right-hand jaw 1 is provided with the usual stop 4 which is supported on the cap 3 and serves to set or position this jaw in its normal open or matrix line receiving position. The Jaw 1, which is movable inwardly from its stop 4 and toward the jaw 2, has a reciprocating bar 5 fastened thereto, and

this bar is connected to a jaw closing mechanism which operates to move the jaw 1 inwardly or toward the jaw 2 to close against a matrix line after the latter has been presented between the 5 vise jaws and to move the jaw 1 outwardly against its stop after a cast has been made. The jaw closing mechanism shown in the present instance is similar to that shown and described in my prior application, Serial No. 612,349, filed May 19, 1932, 10 it comprising an arm 6 which is pivotally connected to the bar 5 by a link 7, this arm being pivoted at 8 on a stationary part 9 of the machine frame, the arm 6 being connected to an arm 10 which is operatively connected by a spring 11 15 to a lever 12, the latter being pivoted at 13 on a stationary part of the machine frame and having a forked rear end which straddles the usual cam shaft 15 on the machine, the arms of the cam fork of the lever 12 being provided with cam 20 pieces 16 and 17 which are successively engageable by a roller or projection 18 on the cam shaft and operative respectively to close and open the jaw 1 at appropriate times in the cycle of operation of the machine, the jaw 1 being closed 25 against the line yieldably through the action of the spring 11. The lines of matrices M which may be composed in the machine in the usual and well known manner, are received by the jaws 19 of a line transporter which may be the usual 30 so-called first elevator as employed in machines of this class, the matrices in each line being supported in this elevator by the usual lugs or ears which project forwardly and rearwardly from their upper corners and hang from rails on the 35 jaws of the elevator in the usual and well known manner. The line transported or first elevator lowers the matrix lines between the vise jaws and into a position in front of a mold 20 which may be of the form commonly employed in machines of this class, having a slot or cavity in 40 which a type bar or slug is cast against the character bearing edges of the matrices presented thereto, by metal injected into the mold from the metal pot in the usual and well known 45 way.

The matrices, as usual in machines of this class, may have upper and lower type forming characters or cavities m located at different heights or levels thereon, as shown in Figure 4, or head 50 letter characters located thereon at the level of the lower character of such two-letter matrices, or the matrices may have relatively large or advertising display characters m' formed thereon at another or lowermost level, as shown in Figure 3, the molds used conforming with the kinds 55 of matrices from which the casts are to be made and the line transporter or first elevator being stopped in its descent so that it will present the matrix lines at the proper alining levels with 60 respect to the mold. The means shown in the present instance for stopping the descent of the first elevator at one or another level corresponding to the alining level at which the matrix lines should be positioned in front of the mold comprises 65 an alining bar 21 which is slidable longitudinally in the top of the vise cap 3, this bar carrying pins 22 and 23 which project upwardly therefrom to different heights, and one or the other of these pins or the top of the bar 21 is 70 engageable by an adjustable stop screw 24 which is fitted in the head 25 of the first elevator to stop the descent of the latter at the required height for alining different height characters on the matrices in front of the type bar or slug 75 casting mold, the engagement of the screw 24 di-

rectly with the upper side of the alining bar 21 serving to aline the upper characters on the matrices with the mold slot as shown in Figure 4, the engagement of the screw 24 with the pin 23 serving to aline large or advertising display characters with the mold slot as shown in Figure 3, and the engagement of the screw 24 with the pin 22 serving to aline the lower of the two-letter characters or head letter characters on the matrices with the mold slot, the level to which the first 10 elevator and, in consequence, the matrix line is lowered in front of the mold being controlled by shifting the alining bar 21 longitudinally to bring one or the other of the pins 22 and 23 or the top surface of the bar 21 into position beneath 15 the screw 24 on the first elevator.

In order to retain the vise jaw 1 against movement inwardly or against the matrix line until the line is lowered between the vise jaws, a latch 23 is provided, this latch in the present instance being pivoted at 27 to a bracket 28 which is fixed to the top of the vise cap and may serve to support the stop screw 4 for the jaw 1. The latch 26 has a downwardly projecting portion 26a which is engageable in a notch 5a in the bar 5, the latch 25 26 normally resting by gravity with its downwardly extending portion 26a engaged in the notch 5a in the bar 5 and thereby retaining the jaw 1 connected to the bar 5 in its normal open or matrix line receiving position against the stop 30 4, and an upward swing of the latch about its pivot 27 serving to disengage the portion 26a from the notch 5a and thereby releasing the jaw 1 for inward movement against the matrix line.

According to the present invention, a latch releasing member or pawl 29 is pivoted at 30 to the latch 26 and has a toe 31 which projects into the path of one of the jaws 19 of the first elevator so that it will be depressed as the first elevator descends to present a matrix line between the 40 vise jaws and in front of the mold. A block 32 is fixed on the alining bar 21 by a screw 33 which preferably engages in an elongated slot 34 which enables the block 32 to be adjusted longitudinally of the alining bar 21, and the block 45 32 is preferably provided with an indicator mark 35 and the top of the vise cap 3 is provided with cooperating indicating marks with which the indicator mark 35 may register to indicate the different settings for the alining bar 21, the indicator marks shown in the present instance on the vise cap being "Normal", "H. L." and "High" and designating and corresponding with the setting of the alining bar 21 to arrest the descent of the first elevator respectively at the normal alinement 55 level at which the stop screw 24 on the first elevator directly engages the top of the alining bar, the intermediate or head letter alinement level at which the screw 24 engages the lower alining pin 22, and the high alinement level at 60 which the stop screw 24 engages the higher alining pin 23 and thereby arrests the descent of the first elevator at the highest level as shown in Figures 1 and 3. The block 32 has a pivot or fulcrum pin 36 projecting therefrom and into a slot 37 65 formed in the releasing member or pawl 29, this pin being shiftable longitudinally in said slot when the alining bar 21 is shifted longitudinally to set it in one or another of the positions described to control the extent of descent of the 70 first elevator, the slot 37 being so shaped that the pivot or fulcrum pin 36 will position the toe 31 on the releasing member 39 at such a height as to cause it to be engaged and actuated to release the latch when the elevator is within the same 75

distance of its final stopping point, whether the alining bar 21 is set for the highest or lowest alinement levels or for the intermediate alinement level. For example, Figures 6 and 7 show the pivot or fulcrum pin 36 respectively at the opposite ends of the slot 37 corresponding to the setting of the alining bar 21 for normal or lowest and the highest alining positions respectively, and it will be seen from these figures that the first elevator will strike and depress the toe 31 of the releasing member 29, in each instance, when the first elevator is within the same distance X of its final stopping point. When the alining bar 21 is set in an intermediate position for the stopping of the first elevator at the intermediate level, the pivot or fulcrum screw 36 will rest at an intermediate point in the length of the slot 37, and the toe 31 of the releasing member will then be set at such a height that it will be engaged and depressed by the first elevator when the latter is within the same distance of its final intermediate stopping point as indicated by the distance X in Figures 6 and 7. Since the pivot or fulcrum pin 36 is supported by the alining bar 21 at a point between the toe 31 of the releasing member 29 and the pivot 30 which connects said member to the latch 26, depression of the toe 31 by the descending first elevator will rock the portion 26a of the latch upwardly out of the notch 5a in the bar 5, thereby releasing this bar and the movable jaw 1 connected thereto so that the latter may close against the matrix line, and since the pin 36 is carried by the alining bar 21 so that it is shiftable therewith, the setting of the releasing member 29 for the release of the jaw 1 is controlled by or coordinated with the setting of the alining bar to determine the level to which the first elevator lowers the matrix lines between the vise jaws.

In operation, sliding of the alining bar 21 to bring the indicator mark 35 into register with the mark on the vise jaw corresponding to the desired setting of the alining bar positions the alining bar to stop the descent of the first elevator at the desired level and also shifts the pin 36 in the slot 37 of the latch releasing member 29 and thereby automatically rocks the member 29 to raise or lower its toe 31, according to the direction in which the alining bar is moved, Figure 6 showing the releasing member 29 in its highest position corresponding to the position of the parts in Figure 1 wherein the high alinement pin 23 stands beneath the stop screw 24 conforming with the setting of the indicator mark 35 in register with the "High" indicator mark on the vise cap as shown in Figure 2, and the pin 36 stands at the right hand end of the slot 37, and Figure 7 showing the latch releasing member 29 in its lowest position corresponding to the position of the alining bar 21 when set with its indicator mark 35 in register with the "Normal" indicating mark on the vise cap when the screw 24 will be engageable directly with the top of the alining bar, the pin 36 being then shifted to the left hand end of the slot 37 in the latch releasing member 29 and the latter then occupying its lowest position. Setting of the alining bar 21 in an intermediate position so that the indicator mark 35 thereon registers with the "H. L." indicator mark on the vise cap will bring the alining pin 22 into position beneath the screw 24 to stop the descent of the first elevator at an intermediate level and this setting of the alining bar 21 will concurrently set the pin 36 at a point intermediately of the length of the slot 37 in the

latch releasing member 29 and will thereby set this member with its toe 31 at an intermediate height. Thus, for each setting of the alining bar 21 to determine the level to which the first elevator descends to present the matrix line between the vise jaws, the toe 31 of the latch releasing member 29 will be positioned at such a height that it will always be struck by the first elevator when the latter is the same distance above its alining stop, so that the jaw retaining latch 26 will always be tripped to release the jaw 1 for inward movement under the action of the closing mechanism when the matrix line has been brought down between the jaws to the lowest point possible for any given alinement and hence premature releasing of the vise jaw and consequent interference with the proper presentation of the matrix lines between the vise jaws and in front of the mold is avoided.

While the movable vise jaw 1, as hereinbefore described, will be released by the latch 26, in accordance with the setting of the first elevator alining bar 21, for movement from its normal open position against its stop 4 toward the other jaw 2, under the action of the jaw closing mechanism, to clamp each matrix line in casting position in front of the mold, the return movement of the jaw 1 to its normal open position against its stop 4, under the action of the jaw closing mechanism, following each cast, will cause the jaw 1 to be retained in its normal open or matrix line receiving position by the latching of the portion 26a of the latch 26 over the end of the bar 5 and the re-engagement of the portion 26a of the latch in the notch 5a of the bar 5, the latch and its releasing member being thus reset ready for the release and closing of the jaw 1 against the next line introduced between the vise jaws.

I claim as my invention:

1. In a line casting machine having a matrix line receiving vise embodying jaws at least one of which is movable from matrix line receiving position toward the other jaw to close against matrix lines, a matrix line transporter and means cooperative with said transporter to cause it to present matrix lines between the vise jaws at relatively different alinement levels, means for retaining the movable jaw in line receiving position and control means therefor independent of the transporter and adjustable to cause said movable jaw to be released automatically when the transporter reaches one or another alinement level.

2. In a line casting machine having a matrix line receiving vise embodying jaws, one of which is movable from a normal matrix line receiving position toward the other jaw to close against matrix lines, and a matrix line transporter, alining means cooperative with the transporter and capable of being set to cause the transporter to present matrix lines at relatively different alinement levels between the jaws, retaining means for holding the movable jaw in normal position, a releasing member for the retaining means capable of being set to release the retaining means to conform with the presentation of the matrix lines at different levels between the jaws, and an intercontrolling connection between said alining means and latch releasing member.

3. In a line casting machine having a vise embodying jaws one of which is movable from matrix line receiving position toward the other jaw to close against matrix lines, a matrix line transporter, and alining means capable of being set to cause said transporter to present matrix lines between the vise jaws at different levels, means for

retaining said movable jaw in matrix line receiving position, and means governed according to the setting of said alining means and controlled by the matrix line transporter for releasing said

5 jaw retaining means.

4. In a line casting machine having a matrix line receiving vise embodying jaws one of which is movable from matrix line receiving position toward the other jaw to close against matrix lines, 10 and a matrix line transporter and cooperative setting means for presenting matrix lines between the vise jaws at different alinement levels, releasable retaining means for holding the movable jaw in matrix line receiving position, and means connected to said setting means to be controlled by the setting thereof and actuated by the matrix line transporter to release said jaw retaining means in accordance with the alinement level 15 at which the transporter presents the matrix lines between the vise jaws.

20 5. In a line casting machine having a matrix line receiving vise embodying jaws one of which is movable from matrix line receiving position toward the other jaw, means connected to said movable jaw and operative to close it against matrix lines, and a line transporter and cooperative setting means for presenting matrix lines between the vise jaws at relatively different alinement levels, retaining means for holding the movable jaw in matrix line receiving position, and a releasing member for said retaining means set in one or another position in accordance with the setting of said setting means for actuation by the transporter to release the jaw retaining means 35 when the transporter reaches a position corresponding to the setting of said setting means.

25 6. In a line casting machine having a matrix line receiving vise embodying jaws one of which is movable from matrix line receiving position toward the other jaw to close against matrix lines, a line transporter for introducing matrix lines between the jaws, and an alining bar capable of being set in different positions and operative to stop the transporter in different positions 40 to present matrix lines between the jaws at different alinement levels, retaining means for holding the movable jaw in line receiving position, a releasing member for said retaining means engageable by the transporter for actuation thereby, and a controlling member for the releasing member connected to the alining bar to be set thereby and operative to position said releasing

member for actuation by the transporter when the latter approaches the matrix line presenting position determined by the setting of the alining bar.

7. In a line casting machine having a matrix line receiving vise embodying jaws one of which is movable from a normal matrix line receiving position toward the other jaw to close against matrix lines, and an elevator for lowering matrix lines into position between the jaws at relatively different levels, a latch for holding the movable jaw in normal matrix line receiving position, a releasing member for the latch in the path of the elevator to be actuated thereby, and means for setting the releasing member in different 10 positions to release the latch in conformity with the respective levels at which the elevator positions the matrix lines.

8. In a line casting machine having a matrix line receiving vise embodying jaws one of which is movable from a normal matrix line receiving position toward the other jaw to close against matrix lines, and an elevator for lowering matrix lines into position between the jaws at relatively different alinement levels, a pivoted latch for 20 retaining the movable jaw in normal position, a releasing member pivoted to the latch and projecting into the path of the elevator to be actuated thereby during its descent, and a fulcrum for the releasing member shiftable to vary the 25 position of the releasing member relatively to the direction of movement of the elevator to effect actuation thereof in accordance with the level at which the elevator positions the matrix lines between the jaws.

35 9. In a line casting machine having a matrix line receiving vise embodying jaws, one of which is movable from matrix line receiving position toward the other jaw, actuating means for the movable jaw to close said jaw against matrix 40 lines, a line transporter, and setting means cooperative with the transporter for causing it to present matrix lines between the vise jaws at different alinement levels, means acting to hold the movable jaw in matrix line receiving position, and means governed by said setting means and operative upon presentation of the line by the line transporter at one or another alinement level to render ineffective the action of said holding means and thereby permit the actuating 45 means to close the movable jaw.

SAMUEL E. SPERRY.
